UNITED STATES PATENT OFFICE.

JOHN A. MANDIS, OF HIGHLAND, MICHIGAN.

NECKTIE-HOLDER.

1,370,468.

Specification of Letters Patent.

Patented Mar. 1, 1921.

Application filed June 8, 1920. Serial No. 387,453.

To all whom it may concern:

Be it known that I, JOHN A. MANDIS, a citizen of the United States, residing at Highland, in the county of Wayne and State 5 of Michigan, have invented new and useful Improvements in Necktie-Holders, of which the following is a specification.

This invention relates to clasps or fasteners and has for its object the provision of a 10 novel fastening device adapted to be passed through a neck tie and through a shirt front, or a button-hole in the latter whereby to hold the tie straight and prevent it not only from blowing, but from any lateral derangement.

An important object is the provision of a device of this character which includes a pair of separable members, one adapted for disposition at the front of the tie and the 20 other adapted for straddling engagement upon the shirt front, these members being detachably connected and novel means being provided for preventing casual separation thereof.

An additional object is the provision of a 25 device of this character which will not only be neat and attractive in appearance, but which will also be highly efficient in use, durable in service, as well as inexpensive to 30 manufacture, and a general improvement in the art.

With the above and other objects and advantages in view, the invention consists in the details of construction to be herein- 35 after more fully described and claimed, and illustrated in the accompanying drawings in which—

Figure 1 is a front elevation of my device upon a neck tie,

Fig. 2 is a rear elevation of my device, Fig. 3 is a side elevation,

Fig. 4 is an enlarged front elevation with the parts in clamped position,

Fig. 5 is an enlarged front elevation showing the rear member alone and in released position.

Fig. 6 is a longitudinal sectional view with the parts in interengaged position,

Fig. 7 is a cross sectional view through the upper portion thereof, and

The remaining figures are detail views.

Referring more particularly to the drawings, the letter A designates a neck tie and B designates the front of a shirt. In carrying out my invention I provide a member 10 which is formed from a single piece of

metal bent into U-shape, as shown. The rear arm of this member 10 is formed with a convex projection 11 which is formed centrally with a small hole 12. The front arm 60 of the member 10 is formed with a small hole 13 registering with a hole 12 and counter-sunk, as shown at 14, to define a flaring entrance opening.

Disposed within the member 10 is a pair 65 of members 15, each of which is formed from a single piece of metal and including spaced blade-like portions 16 and handle portions 17 which are trough-shaped with their closed sides outermost. These members 15 are pivoted at 18, and the pivot is surrounded by a spring 19 having the ends of its arms engaging the handle members 17 for normally forcing the handle members apart. The members 15 are so 70 arranged that the blade portions 16 thereof will overlap and each pair of blade members is formed with arcuate slots 20.

Associated with this portion of the device is a head 21 formed preferably as a plate 80 of any desired shape and size and which may be made highly ornamental if desired. This head carries a shank 22 which is pointed and which is adapted to be passed through the neck tie.

85 The use of the device is as follows:

The pointed shank 22 is forced through the neck tie with the head 21 disposed against the outer side thereof. The head is so positioned that the shank 22 may be 90 passed through a button-hole in the front of the shirt or may be pushed through the front of the shirt, as preferred, it really making no difference which mode of procedure is adopted as the shank 22 is nothing much 95 more than a pin. The operator then grasps the other or U-shaped portion of the device first described, and places it in straddling engagement upon the shirt front with the shirt front engaged between the blades, and 100 then engages his fingers against the outer sides of the handle members 17, after which he presses these members together which results in swinging the blade portions 16 into overlapping relation within the confines of 105 the body 10. This brings the slots 20 in registering position. The shank 22 is then inserted through the hole 13, through the slots 20, and through the hole 12, after which the operator releases his grasp upon 110 the handle members 17 whereupon the spring 19 operating to force the handle

members apart will cause the ends of the slots 20 to engage the shank 22 and grip it so as to prevent the shank from being withdrawn. When the device is thus applied, it is apparent that the neck tie will be firmly held in proper position so that it cannot be displaced from any cause.

While I have shown and described the preferred embodiment of my invention, it 10 is of course to be understood that I reserve the right to make such changes in the form, construction, and arrangement of parts as will not depart from the spirit of the invention or the scope of the subjoined claims.

15 Having thus described my invention, I claim:

1. A neck tie holder comprising in combination, a U-shaped body provided with registering holes, a pair of outwardly sprung 20 pressed members pivoted within said body and including blade portions arranged in overlapping relation and formed with arcuate slots; and a head carrying a pointed shank passable through a tie and a shirt 25 front with the point passing through the

holes and the slots in said body and blade members respectively.

2. A device of the character described comprising a member disposable in straddling engagement upon a shirt front and 30 formed as a U-shaped body provided with registering holes, a pair of members arranged in crossed relation and pivoted within said body, a spring normally urging said members apart, said members being formed 35 adjacent the bight of the body with channel-shaped portions having their sides outermost and constituting handles, said members being formed adjacent their outer ends with arcuate slots adapted to be brought 40 into registration with each other and with said holes, and a head disposable against the front of the tie and carrying a pointed shank passable through the tie and the shirt 45 front and engageable through said holes and the slots when said handle portions are brought together.

In testimony whereof I affix my signature.

JOHN A. MANDIS.
